UNITED STATES PATENT OFFICE

GEORGE M. EAMES, OF BRIDGEPORT, CONNECTICUT, AND IRVING F. WEBB, OF ELIZABETH, NEW JERSEY, ASSIGNORS TO THE SINGER MANUFACTURING COMPANY, OF ELIZABETH, NEW JERSEY, A CORPORATION OF NEW JERSEY

POWER TABLE TROUGH

Application filed July 2, 1926. Serial No. 120,015.

This invention relates to improvements in power-tables for sewing machines and the like, and more particularly in trough constructions for power-tables of this character.

For certain classes of work, it has been a common practice in the construction of sewing machine power-tables to provide work-receiving troughs longitudinally of the table-tops thereof. Various expedients have been employed for supporting the troughs, a very common type comprising specially shaped brackets which were secured to the table-legs or cross rails and to which brackets the side and bottom members of the troughs were suitably bolted. Brackets of this character of course add material to the cost of a power-table both as to material and in time consumed in bolting the trough members thereto. Furthermore, brackets of this character are in the main capable of being used only with the particular table-structure for which they have been designed, different constructions being usually required for single and double types of tables. In some instances, the trough members have been permanently assembled by rigidly securing the side members to the bottom member and the assembled trough was then suspended from the table-top or its supporting structure. This latter expedient, owing to transportation difficulties, however, requires considerable time and therefore expense in installing a power-table.

The present invention has for its objects to simplify the construction of a power-table trough; to provide a trough equally adaptable to single and double types of power-tables; to provide for the ready conversion of a flat-type power-table to the trough type, and to provide a construction permitting of the ready attachment of a trough to table structures of different characters.

In the preferred embodiment of the present invention, the side-members of the trough

are free of auxiliary brackets and securing bolts and instead of being suspended from the table-structure, they are clamped thereto by interposing said side-members between the table-top and the trough bottom-clamped by suitable bolts to the overlying table-structure. A shoulder-joint connection between the lower edges of the side-members and the bottom-member is employed to facilitate assembling of the parts and to restrain the lower edges of said side-members against lateral movement, the upper edges of the side-members being held against movement by the regular table structure. Only one clamping bolt need be employed at each end of a table-section and aside from an underlying clamp-plate for supporting adjacent ends of bottom trough-members in a sectional power-table, the clamping bolts referred to constitute the sole means additional to a table-structure for supporting its trough.

In the accompanying drawings, Fig. 1 is an end view of the double type of power-table, showing the upper portion only of the table-legs. Fig. 2 is an enlarged cross-section substantially on the line A—A, Fig. 1, and illustrates the connection between adjacent table-sections. Fig. 3 is a central longitudinal section of the power-table, i. e., substantially on the line B—B, Fig. 1. Fig. 4 is a transverse cross-section, partly in elevation, of the single type of power-table.

The drawings illustrate a table-supporting structure constructed substantially in accordance with that more fully disclosed in my prior patent application, Serial No. 95,848, filed March 19, 1926. Said supporting structure includes primary, channel-bar leg-members 1 of which the upper ends are entered by secondary, channel-bar leg-members 2 for vertical adjustment therein, the complementary leg-members being secured in adjusted position as by means of a bolt 3. The upper ends of the leg-members 2 are each rigidly secured, as by welding or riveting, within

the channel of an inverted U-shaped channel-bar 4 comprising a transverse rail for supporting the table-top, it being of course understood that a rail with its supporting leg-members is disposed at the abutting ends of adjacent table-sections as well as at the table-ends. As shown more clearly in Fig. 2 of the drawings, the rails 4 are connected by cross-rods 5 secured upon the rails by bolts, as 6, the flattened ends of the cross-rods 5 overlapping on the rails supporting the tops of adjacent table-sections.

In a double type of power-table, as shown in Figs. 1, 2 and 3 of the drawings, the rails 4 carry front and rear machine-supporting planks, as 7, the abutting ends of corresponding planks of adjacent table-sections being secured upon the rails 4 by bolts, as 8, connecting upper clamp-members 9 and lower clamp-plates 10. At the outer ends of the power-table, a strip 11 is inserted under the upper clamp-member 9, in lieu of a machine-supporting plank of a succeeding table-section. The inner longitudinal edges of the planks 7 are undercut to provide a shouldered recess 12 affording clearance for the rail-connecting rods 5, and in a flat-type table to also provide for the reception of the longitudinal edges of an intermediate plank (not shown) bridging the space between the machine supporting planks 7. In a trough-type table, the intermediate planks of the flat-type table are omitted and strips, as 13, are substituted therefor to cover the rails 4. From the foregoing it is to be understood that the machine planks and the supporting structure therefor are standard for flat and trough types of tables.

While the present improved trough has been applied to a power-table of the construction described, its principle of construction is such as to render it adaptable for various makes of power-tables and therefore the present invention has a wide scope of commercial application. As shown in the drawings, the trough comprises inclined side-members 14 converging toward and seated upon a bottom-member 15, a shoulder-joint connection being formed between the lower edges of the side-members and the bottom-member by, in the present instance, forming rabbets 16 in the longitudinal edges of the bottom-member 15 and by correspondingly shaping said lower edges of the side-members 14. The upper corners of the side-members 14 are cut away to provide complementary notches 17 receiving the rails 4, while the upper longitudinal edges of said side-members 14 are preferably beveled at their outer sides to form vertical surfaces resting against the cross-rods 5.

The side-members 14 and the bottom-members 15 each extend the length of a table-section and the abutting ends 18 of the bottom-members of adjacent table-sections are each

supported by an underlying clamp-plate 19 apertured to receive a bolt 20 passing through aligned apertures in the rail 4 and the strips 13 overlying said rails. By tightening the nut 21 of the bolt 20, the upper edges of the side-members 14 are clamped against the planks 7, i. e., in the recesses 12 thereof, said side-members being held against lateral movement by the cross-rods 5 and the bottom-member rabbets 16.

From the foregoing, it will be understood that the securing means for the trough of a table-section in addition to the regular table-structure, comprises merely a clamp-plate 19 and a bolt 20 disposed at each end of a table-section and that one bolt and clamp-plate suffice for rigidly securing the abutting trough member ends of adjacent table-sections. A particular feature of the present improvement is the facility with which the trough-members may be assembled in applying them to a power-table. The trough bottom-members are first loosely suspended below the table by the bolts 20 to provide sufficient clearance for individually inserting the side-members, and after insertion of the side-members, the nuts 21 are tightened to rigidly clamp the several members in position. Should it be desired to remove either of the planks 7 for any reason, this may be done without dismantling the trough, because the walls of the side-member notches 17, together with the cross-rods 5 and the rabbets 16 prevent any material movement of the side-members 14 in the absence of the planks 7.

Preferably the trough is closed at the ends of the power-table by transverse end-members 22 each supported by an end clamp-plate 19 and extending within the channel of a rail 4, being of course held in this position by the bolt 20 at the end of the table. If desired, the end-members 22 may be each provided with a clean-out aperture 23 which may be normally closed by a closure-plate 24, pivotally secured upon the member 22 by a screw 110 25. Should it be desired to divide the trough into sections corresponding to the length of the table-sections, adjacent division-walls 26 and 27, as shown in Fig. 3 of the drawings, may be inserted in the channels of the rails 115 4 so as to be disposed transversely of the length of the trough, said walls being suitably shaped to correspond to the contour of the trough and adjacent walls being vertically moved to provide an aperture for a 120 bolt 20.

The power-table illustrated in Fig. 4 differs from the one heretofore described in having a shorter rail 4 to carry a machine supporting plank 7 at one end only of said rail, i. e., it is a single type power-table. Secured upon the end of each rail opposite to the plank 7, by a U-shaped clamp 28 and a bolt 29, is an undercut strip 30 extending longitudinally of the table and functioning to clamp 125 31

the transverse strip 13 to the rail. In this type of table, the rear side member of the trough is clamped against the recess walls of the strip 30 instead of against the table-top plank 7.

Having thus set forth the nature of the invention, what we claim herein is:

1. A trough construction for power-tables including a table-top supporting structure, comprising a trough bottom-member, inclined trough side-members interposed between the bottom-member and the table-top, and means detachably clamping the trough bottom-member against the interposed side-members to thereby clamp said side- and bottom-members to the table-top, a shoulder-joint constituting the connection between the side- and bottom-members to restrain said side members against lateral movement in clamped position.

2. In a power-table, the combination with a table-top, and transverse table-top supporting rails, of a trough disposed longitudinally of said table-top, said trough comprising side-members recessed to provide clearance for said rails and a trough bottom-member sustaining said side-members, and bolts connecting said rails and the trough bottom-member to thereby clamp the trough side-members against the table-top.

3. In a power-table, the combination with a table-top, and a table-top supporting structure, of a trough disposed longitudinally of said table-top comprising sectional units each composed of side- and bottom-members, clamp-plates underlying the abutting ends of adjacent bottom-members, and bolts extending through said trough connecting said clamp-plates with the table-structure and clamping said bottom-members against the trough side-members to thereby clamp said side-members against the table-structure.

4. In a power-table, the combination with a table-top, and a table-top supporting structure, of a trough comprising a bottom-member, side-members converging toward said bottom-member, trough-end closing members, clamp-plate underlying the adjacent ends of said trough-bottom and trough-end closing members, and bolts connecting said clamp-plates with the table-structure for simultaneously clamping all of said members in trough-forming position.

5. In a power-table, the combination with a table-top, and a plurality of table-top supporting channel-bar rails disposed transversely of the length of the table-top, of a sectional trough disposed longitudinally of said table-top comprising abutting bottom-member sections, side-member sections converging toward said bottom-members, trough-end closing members projecting with in the channels of the table end-rails, trough dividing members disposed at the abutting points of adjacent trough sections and pro-

jecting within the channels of the intermediate rails, clamp-plates underlying the ends of said bottom-member sections, and bolts connecting said clamp-plates with said rails to thereby simultaneously clamp all of said members in trough-forming position.

6. A power-table, comprising table-supporting standards, a table-top sustained by said standards, and a trough disposed longitudinally of said table-top, said trough consisting of side- and bottom-members, and securing means located between the side-members and in the trough engaging the bottom-member to clamp the side-members to the table-top.

7. A trough-type power-table, comprising supporting standards, including end-rails disposed transversely of the length of the power-table, a table-top sustained by said end-rails, a trough comprising bottom and opposed side-members disposed longitudinally of the power-table and extending below said rails, and trough-securing means depending from the end-rails exerting a force on the bottom-member below said rails in a direction toward the table-top for thereby detachably clamping the trough side-members in trough-forming position upon the table structure.

8. A trough construction for power-tables having table-top supporting end-rails, comprising a trough bottom-member, inclined trough side-members interposed between said bottom-member and the table-top, said trough-members being disposed longitudinally of the table-top and extending below said end-rails, securing means depending from the end rails exerting a force upon the bottom-member below said rails in a direction toward the table-top for thereby clamp the trough side-members upon the table structure, and means for restraining the trough side-members against movement crosswise of the trough bottom-member.

9. A trough construction for power-tables having table-top supporting end-rails, a trough bottom-member, inclined trough side-members interposed between the trough bottom-member and the table-top, said trough-members being disposed longitudinally of the table-top and extending below said end-rails, and bolts depending from said end-rails exerting an upward pull upon the trough bottom-member below the end-rails for thereby detachably clamping the trough side-members against the table-top.

10. A trough construction for power-tables having table-top supporting end-rails, comprising a trough bottom-member disposed at a substantial distance below said end-rails, trough side-members converging toward the bottom-member, said trough-members providing a continuous trough opening between the ends of the power-table and extending below said end-rails, means

exerting a force in the direction of the table-top for detachably clamping the trough side-members between the trough bottom-member and the table-top, and means for holding both side edges of each of said side-members against lateral movement in clamped position.

In testimony whereof, we have signed our names to this specification.
